(57) **CLAIM**

The ornamental design for a weight, as shown and described.

DESCRIPTION

FIG. 1 is a front elevation view of a weight showing our new design, according to a first embodiment;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a top-front-right perspective view thereof;

FIG. 8 is a bottom-rear-left perspective view thereof;

FIG. 9 is a top-rear-left perspective view thereof;

FIG. 10 is a bottom-rear-right perspective view thereof;

FIG. 11 is a front elevation view of a weight showing our new design, according to a second embodiment;

FIG. 12 is a rear elevation view thereof;

FIG. 13 is a right side elevation view thereof;

FIG. 14 is a left side elevation view thereof;

FIG. 15 is a top plan view thereof;

FIG. 16 is a bottom plan view thereof;

FIG. 17 is a top-front-right perspective view thereof;

FIG. 18 is a bottom-rear-left perspective view thereof;

FIG. 19 is a top-rear-left perspective view thereof;

FIG. 20 is a bottom-rear-right perspective view thereof;

FIG. 21 is a front elevation view of a weight (e.g., an exercise weight for resistance exercises or other human physical fitness activities), showing our new design, according to a third embodiment;

FIG. 22 is a rear elevation view thereof;

FIG. 23 is a right side elevation view thereof;

FIG. 24 is a left side elevation view thereof;

FIG. 25 is a top plan view thereof;

FIG. 26 is a bottom plan view thereof;

(Continued)

FIG. 27 is a top-front-right perspective view thereof;
 FIG. 28 is a bottom-rear-left perspective view thereof;
 FIG. 29 is a top-rear-left perspective view thereof;
 FIG. 30 is a bottom-rear-right perspective view thereof;
 FIG. 31 is a front elevation view of a weight (e.g., an exercise weight for resistance exercises or other human physical fitness activities), showing our new design, according to a fourth embodiment;
 FIG. 32 is a rear elevation view thereof;
 FIG. 33 is a right side elevation view thereof;
 FIG. 34 is a left side elevation view thereof;
 FIG. 35 is a top plan view thereof;
 FIG. 36 is a bottom plan view thereof;
 FIG. 37 is a top-front-right perspective view thereof;
 FIG. 38 is a bottom-rear-left perspective view thereof;
 FIG. 39 is a top-rear-left perspective view thereof;
 FIG. 40 is a bottom-rear-right perspective view thereof;
 FIG. 41 is a front elevation view of a weight (e.g., an exercise weight for resistance exercises or other human physical fitness activities), showing our new design, according to a fifth embodiment;
 FIG. 42 is a rear elevation view thereof;
 FIG. 43 is a right side elevation view thereof;
 FIG. 44 is a left side elevation view thereof;
 FIG. 45 is a top plan view thereof;
 FIG. 46 is a bottom plan view thereof;
 FIG. 47 is a top-front-right perspective view thereof;
 FIG. 48 is a bottom-rear-left perspective view thereof;
 FIG. 49 is a top-rear-left perspective view thereof; and,
 FIG. 50 is a bottom-rear-right perspective view thereof.
 The shade lines show surface contour and not surface ornamentation.
